UNITED STATES PATENT OFFICE.

JOHN L. WHEELER, OF ST. LOUIS, MISSOURI, ASSIGNOR TO THE MEASUREGRAPH COMPANY, OF ST. LOUIS, MISSOURI, A CORPORATION OF DELAWARE.

PRESSER ROLLER.

Application filed September 20, 1920. Serial No. 411,501.

To all whom it may concern:

Be it known that I, JOHN L. WHEELER, a citizen of the United States, residing in the city of St. Louis and State of Missouri, have invented new and useful Improvements in Presser Rollers, of which the following is a specification.

This invention relates to measuring machines and is particularly applicable to fabric measuring machines which embody in their construction a measuring roller and a co-operating presser roller which holds the fabric against the face of the measuring roller. In the operation of such a machine the fabric should be drawn in a straight line between the rollers in a direction extending at right angles to the axes of the rollers. In practice, however, the operator of such a machine pulls the cloth or fabric through it in a more or less oblique, inclined or curved direction; the result of this is that the movement of the face of the measuring roller is not a true index of the amount of fabric pulled through the machine, and hence, the indicating mechanism which is actuated by the measuring roller does not truly indicate the length of the fabric measured. The general object of the present invention is to overcome this defect and provide means for insuring an accurate indication by the indicating mechanism in spite of the fact that in operating the machine the fabric has been drawn in an oblique direction between the rollers. More specifically stated as applied to a fabric measuring machine the invention consists in providing a novel construction for the presser roller which will co-operate with the measuring roller in such a way as to affect the movement which is imparted to the measuring roller by pulling the fabric across its face and between the presser roller and the measuring roller, thereby giving the measuring roller an amount of movement that more accurately corresponds to the length of fabric pulled past the measuring roller.

Further objects of the invention will appear hereinafter.

The invention consists in the novel features, and in the general combination of parts to be particularly described hereinafter, all of which contribute to produce a simple and efficient presser roller. A preferred embodiment of my invention will be particularly described in the following spec-

ification, while the broad scope of my invention will be pointed out in the appended claims.

In the drawing;

Figure 1 is a vertical section through a fabric measuring machine of a common type, to which I have applied my invention; and

Figure 2 is a horizontal section taken about on the line 2—2 through the presser roller, illustrating the preferred construction of the presser roller and also indicating the manner in which the presser roller co-operates to give the desired effect.

The machine illustrated comprises a casing or case 1 in the lower portion of which there is rotatably mounted a measuring roller 2, the shaft 3 of which is rotated when the measuring roller rotates, the rotation of the shaft 3 being imparted to indicating mechanism of any kind (not illustrated) that indicates the length of movement of the face of the roller 2. Co-operating with the measuring roller 1 provide a presser roller 4 which is preferably mounted upon a presser roller frame 5 including an arm 6. Associated with this frame there is provided a spring 7 the function of which is to force the presser roller 4 down upon the fabric and press the same against the upper face of the measuring roller. In the machine illustrated the casing is provided with a gap 8 through which the fabric is drawn in the direction indicated by the arrow adjacent to the line 9. With such a machine, if the fabric is pulled in a straight line between the rollers the face of the measuring roller will receive a movement from the fabric which is equal to the amount of movement of the fabric, but the operator of such a machine usually pulls the fabric through the machine in an oblique curved or inclined direction. The effect of this is clearly illustrated in Figure 2. In this view the position of the operator is somewhere near the point 10. In pulling the fabric through the machine the fabric is seized by the operator's hand near the point 11 on the line 9 and is then pulled toward the left as viewed in Figure 1. However, in describing this movement the operator unconsciously advances the fabric, usually not in a straight line but in a curved or oblique line about a radius the center of which lies near the operator's position 10. The result of such a movement with an ordi-

nary presser roller would be to impart a movement to the face of the measuring roller corresponding to the maximum amount of movement given to the fabric at any point. 5 In order to prevent this and in order to impart a more accurate movement to the measuring roller I construct the presser roller 4 so that it consists of a plurality of roller sections 12. These roller sections are simply 10 short rollers or spools supported on the presser roller frame 5 so that they will rotate about a common axis. For this purpose I provide the arm 6 of the presser roller frame with an arbor 13 which is disposed 15 parallel to the axis of the measuring roller 2. The roller sections 12 are simply mounted in a row on this arbor so that their end faces 14 abut against each other and they are held in this close alining relation by a 20 nut 15 mounted on the threaded end of the arbor. In order to exclude lint from the joints in the presser roller 4 which are formed by the abutting end faces 14 of the 25 roller sections I provide small rings 16 which may be in the form of loose slip rings fitting over the abutting ends of the rollers. Each roller section is covered by clothing or a facing composition 17 and this clothing projects outwardly beyond the 30 rings 16, that is to say, the diameter of all the roller sections 12 is the same measured over the clothing 17 and is greater than the diameter of the slip rings.

The manner in which the presser roller 35 of this construction co-operates with the measuring roller to attain the desired effect will be understood by observing the oblique or curved lines 18 and 19 which are arcs struck from the point 10 as a center. These 40 arcs 18 and 19 indicate in a general way the direction of movement of the corresponding parts of the fabric. Evidently the fabric lying near the position of the line 18 will have a greater movement than that lying 45 near the arc 19. Similarly fabric lying adjacent the position of the arc 20 will have a greater movement than the fabric lying near the intermediate arc 21. With a presser roller composed of sections 12 as illustrated, 50 each section tends to impart to the measuring roller a movement corresponding to the amount of movement of the fabric adjacent to that roller section. As a result of this, each roller section tends to produce a different 55 amount of movement in the measuring roller from that of any other section. The

result of this is that the amount of movement imparted to the face of the measuring roller will be an average of the amount of movements which all the different roller sections tend to impart. In other words, the measuring roller will receive a movement corresponding to the fabric which lies adjacent to the intermediate dotted line 22. This will give a movement of the measuring 65 roller which accurately indicates the actual movement of the fabric past the roller, and hence, the measurement indicated by the indicating mechanism will more accurately indicate the actual amount of cloth or fabric 70 measured.

It is understood that the embodiment of the invention described herein is only one of the many embodiments my invention may take, and I do not wish to be limited in 75 the practice of my invention nor in my claims, to the particular embodiment set forth.

I claim:

1. In a fabric measuring machine, the 80 combination of a measuring roller, and a presser roller for pressing the fabric against the face of the measuring roller, consisting of a plurality of independently rotatable sections of equal diameter and supported to 85 rotate on a common axis.

2. In a fabric measuring machine, a measuring roller for imparting movement to the indicating mechanism, in combination with a presser roller composed of a plurality of 90 independently rotatable roller sections of equal diameter, and an arbor supporting the roller sections to rotate on an axis parallel with the axis of the measuring roller, said 95 roller sections operating to measure the average length of fabric when the fabric is pulled past the rollers in an oblique path.

3. In a fabric measuring machine having a measuring roller, a presser roller arbor disposed substantially parallel with the axis 100 of the measuring roller, and a plurality of independently rotatable roller sections of equal diameter mounted on the arbor, said roller sections having end faces abutting against each other, rings carried on the abutting ends of the roller sections, and clothing 105 on the roller sections projecting outwardly beyond the rings.

In testimony whereof, I have hereunto set my hand.

JOHN L. WHEELER.
